UNITED STATES PATENT OFFICE

161,294

ELECTRIC LAMP HOLDER

Chester J. Sternaman, Springfield, Ill.

Application March 3, 1950, Serial No. 8,299

Term of patent 14 years

(Cl. D48—20)

To all whom it may concern:

Be it known that I, Chester J. Sternaman, a citizen of the United States, residing at Springfield, Illinois, have invented a new, original, and ornamental Design for an Electric Lamp Holder, of which the following as a specification, reference being had to the accompanying drawings, forming part hereof; in which:

Figure 1 is a side elevational view of an electric lamp holder, showing my new design.

Figure 2 is a front elevational view thereof.

Figure 3 is a rear elevational view.

The broken lines shown in Figure 1 of the drawing, indicating a lamp lens, are for illustrative purposes only.

I claim:

The ornamental design for an electric lamp holder, substantially as shown and described.
CHESTER J. STERNAMAN.
